UNITED STATES PATENT OFFICE.

JOHN H. MURPHY AND ELSTON A. LOTZ, OF ST. LOUIS, MISSOURI.

AIR LOCK.

Application filed August 28, 1925. Serial No. 52,972.

Our invention relates to improvements in air locks and has for its primary object an air lock which is provided with an eccentrically arranged one piece door in the top 5 of the lock so that same can be operated by one man.

A further object is to construct an air lock in which the bottom door is so constructed as to enable it to be operated by 10 one man from the top of the air lock.

By our construction the number of men necessary to operate the air lock is considerably reduced. At the present time with the ordinary construction of air locks, at 15 least two men are required to operate the top door. Two men are required to operate the lower door. A fifth man is necessary to guide the cable through the top of the lock. One man is required in the lock and one 20 caisson worker, making a total of at least seven men. In larger locks, the number of men necessary to operate the top doors is increased on account of the weight of the door.

Another advantage of our construction is that the man inside of the air lock operates the air valve for controlling the admission 25 of air to and from the lock, this saving considerable time. In fact we have found that by the use of our type of air lock, the amount of material moved therethrough can be greatly increased, thus not only a saving 30 in man power and wages is achieved but also an increase in speed, all of which taken 35 together enables us to make a considerable saving in cost. Furthermore our air lock is only about one-half of the weight of the ordinary air lock and can, therefore, be handled and placed in position more readily 40 than the present type of lock.

In the drawings:

Fig. 1 is a side elevation of our device showing the manner in which the bottom door is manipulated from the top of the 45 lock;

Fig. 2 is an enlarged vertical section of our improved air lock;

Fig. 3 is a top plan view of the same;

Fig. 4 is a horizontal section taken on the line 4-4 of Fig. 2, looking in the direction of the arrow;

Fig. 5 is a horizontal section taken on the line 5-5 of Fig. 2 looking in the direction of the arrow;

Fig. 6 is an enlarged fragmental section

showing the manner of packing the shaft on which the lower door is mounted;

Fig. 7 is an enlarged view of one of the upper door hangers showing the adjustable feature;

Fig. 8 is an enlarged view of the blind bearing secured to one end of the lower door shaft; and

Fig. 9 is an enlarged perspective view of the wear plate secured to the top through which the cable passes.

In the construction of our device, we employ an air lock consisting of a cylindrical member 10. This member is provided with a top 11. To the opposite end of the cylindrical member is secured a tapering member 12, which is provided with an outwardly extending flange 13 through which openings are formed so that it can be bolted on to the sleeve 14. This sleeve is designed to be attached to a caisson in the usual manner, which, being well known in the art, will not be described in detail. The top 11 is provided with a flange 15 which fits inside of the cylindrical member 10 and is for the purpose of permitting the rivets 16 to be passed therethrough for securing the top to the cylindrical member. The top is provided with an opening 17, which is eccentric to the top and which is preferably so arranged that its edge will come directly at the center of the top. The edge of this opening at the center is provided with a semi-circular opening 18 to permit the passage of the cable to which the bucket is attached. This cable or bucket is not shown for they form no particular part of our invention and are in common use at the present time.

To the underside of the top 11 is attached a wear block or plate 19, which is provided with a semi-circular opening 20. This opening is arranged in alignment with the opening 18. The block 19 is preferably of hardened tool steel so that the wear of the cable will not enlarge it rapidly, at the same time, should the opening become too large, the block can be removed and a new block inserted.

Secured through the top are spaced apart hangers 21, which are provided with a screw thread shank 22. To these hangers 21 are secured the hinges 23, which hinges are in turn fastened to the lower face of the top door 24. The hangers 21 are adjusted up-

ward and downward by means of the nuts 25. This is for the purpose of permitting the door to be adjusted so that when closed, it will bear evenly all around the opening. 5 Placed on the door is a gasket 26, which is preferably in the form of a rubber ring, and which is held in position on the door by means of a metallic ring 27 through which rivets 28 pass. These rivets also extend through the door. A portion of the ring adjacent the opening 18 is cut away and in this portion is inserted a tool steel plate 29, which is provided with a semi-circular recess 30 and is for the same purpose as the wear plate 19.

Secured to the underside of the top is a brace 31, the purpose of which is to stiffen the top. This brace may be either a T iron, or it may be an angle or a channel as found 20 desirable. The number of braces may also be varied; the purpose of these braces is to prevent the top from bulging due to the air pressure within the casing.

Mounted within the member 12 is a platform or deck 32, which is provided with a central opening 33. This opening is designed to be closed by the door 34 which is provided with a gasket 35 held in position by a ring 36. The door 34 is provided 30 with hinges 37, which are firmly secured to a shaft 38 by means of set screws 39. One end of the shaft 38 is supported in a blind bearing 40, which is preferably welded on to the outside of the tapered member 12. 35 The opposite end of the shaft extends through a bearing 41, which is provided with a packing gland 42. This gland is tightened by means of a nut 43 and in order to prevent the shaft 38 from shifting, a set collar 44 is employed. The projecting portion of the shaft 38 is provided with a square portion 45 over which a lever 46 fits. This lever is held in position by means of a nut 47. Secured to the free end of the 40 lever 46 is the bifurcated end 47 of a rod 48. This rod passes through a guide loop 49 secured to the top of the caisson and is provided on its upper end with the handle 50 by means of which the door can be opened 50 and closed by an operator on top of the casing.

Formed through the deck 32 is an opening 51, which is surrounded by a flange 52. This opening and flange are screw threaded 55 to receive one end of the pipe 53. On the opposite end of this pipe is secured a three way valve 54. From this valve a pipe leads through a flange 55 to the atmosphere, this flange being preferably located near the top 60 of the air lock. The valve 54 is operated by means of a handle 56. This operation will be explained in detail later. Secured to the cylindrical member 10 and adjacent the top and bottom edges thereof are brackets 65 57, which are for the purpose of securing

a ladder 58 so that the operators can enter and leave the air lock. An opening 59 is also formed in the side of the cylindrical member 10 for the admission of an electric cable for the purpose of supplying light 70 within the air lock. An opening 60 is formed through the deck 32 which permits an electric cable to be passed down into the caisson for furnishing light for the workmen therein. Secured to the outer face of 75 the cylindrical member 10 and adjacent the bottom thereof is a flange 61, which is provided with a screw threaded opening 62 to receive a pipe 63. This pipe is fitted with a globe valve 64. The pipe may be used 80 either for air under high pressure so that a pneumatic tool can be worked in the caisson in the event it becomes necessary to do any drilling or a short section of hose 85 65 may be attached thereto for the purpose of washing concrete from the deck and door 34, which is necessary during the time that the caissons are being filled with concrete. The deck 32 is suitably braced by means of braces or brackets 66. The door 24 is 90 also provided with a ring 67 by means of which this door can be closed. The top of the air lock may also be provided with suitable rings 68 for the purpose of attaching hoisting cables thereto for the purpose of 95 moving the air lock from one location to another.

The member 12 is also provided with a screw threaded opening 69, which is located below the deck 32 and which is usually 100 closed with a plug 70, the purpose of this opening is to act as an emergency connection, in case anything should go wrong with the usual air supply, to the caisson as an 105 emergency air line can be attached thereto in a short while so that the air pressure can be maintained in the caisson at all times.

The operation of our device is as follows: After the air lock has been secured to the 110 caisson in the usual manner, the lower door is closed and air supplied to the caisson until the proper pressure has been reached. The caisson worker and the air lock man now enter the air lock. The bucket is lowered 115 into the air lock and the top door closed. The air lock man now manipulates the three way valve in such a manner that air will enter the air lock from the caisson. This 120 air pressure will force the door 24 tightly against the top and prevent any escape of air. When the pressure in the air lock is the same as in the caisson, the door 34 opens and the caisson worker together with the bucket is lowered into the caisson. The 125 caisson worker now fills the bucket and, when it is full, the man in the air lock signals in the usual manner and the bucket is hoisted into the air lock. When the bucket has entered the air lock, the operator again 130

signals, which is the sign to stop hoisting and to close the lower door, which is done by one of the men on top of the air lock pulling up on the lever 48. As soon as the 5 door 34 is closed, the man in the air lock manipulates the handle 56 closing off the pipe 53 and positioning the gate in the valve so that the air from the air lock will escape to the atmosphere. As soon as the pressure 10 in the air lock is reduced sufficiently, the door 24 opens automatically, the door 34 being now held in closed position by the air pressure in the caisson. The bucket together with the material is now removed 15 through the top of the caisson, emptied, and returned to the air lock. The door 24 is again closed by the workers on top of the air lock and the handle 56 manipulated so as to permit air to enter the lock from the 20 caisson. As soon as the air in the lock has reached the same pressure as the air in the caisson, the door 34 swings open automatically and upon a further signal the bucket is again lowered into the caisson.

25 Should it become necessary to use an air drill in the caisson, an air supply pipe is attached to the flange 61 on the outside and an air hose to the inside. This air hose is then led downward through the opening 33 and 30 into the caisson where it is attached to the proper tool and after this work has been done, it is again removed.

When filling the caisson with concrete, the 35 door 34 is closed and the air from the air lock allowed to escape to the atmosphere, the door 24 opened and a batch of concrete poured in, which comes to rest on the door 34 and on the platform 32. The door 24 is then closed and pressure restored to the air 40 lock, which permits the door 34 to open and the concrete to drop into the caisson. When concreting, the globe valve 64 is attached to a water pipe and a short length of hose 65 attached on the inside of the air lock. After 45 the concrete has been dumped, it is obvious that there will be particles of concrete lodged on the door 34 and also on the gasket 50 35, which would prevent proper closing of the door 34 for the introduction of the next batch of concrete.

The hose 65 is now used to wash off the deck and the door so that all parts will be perfectly clean and the door closed properly. By using a hose for this purpose the 55 cleaning can be done more thoroughly and with less use of water than is now done where a short section of rigid pipe with a flattened end is used for this purpose.

Having fully described our invention, 60 what we claim is:—

1. An air lock comprising a cylindrical member, a top having a circular opening eccentrically located therein secured to one end of said cylindrical member, a one piece air 65 tight closure for said circular opening, said

closure and the top each provided with a semicircular passage through which a cable is adapted to pass, said openings being located in the center of the top, a second member secured to the opposite end of said cylindrical member, a deck provided with a central opening located in said second member, a one piece air tight closure for said last mentioned opening, a shaft projecting through one wall of said second member, 70 hinges rigidly secured to said last mentioned closure and said shaft, a lever secured to the projecting end of said shaft, a rod having a bifurcated end secured to said lever and projecting upwardly therefrom so that said closure can be opened and closed from the top of said air lock, a guide-loop carried by the top of said cylindrical member, a hardened wear plate surrounding the semi-circular opening in the top, and a hardened wear plate surrounding the semi-circular opening in the edge of the first mentioned closure. 75

2. An air lock comprising a cylindrical member provided with a top, said top having an opening eccentrically formed therein, a one piece air tight hinged closure for said opening, means whereby said hinged closure can be adjusted for securing an air tight contact, a second member secured to the opposite end of said cylindrical member, a deck provided with a central opening secured to and within said second member, an air tight closure for said central opening, a shaft rigidly secured to said air tight closure and projecting from one side of said cylindrical member, means operable from the top of the closure for rocking said shaft whereby said air tight closure is opened and closed, and means located within the air 105 lock and both closures operated by one man, and a passageway formed in the edges of the opening in the top and of the closure therefor so as to permit the passage of a cable therethrough when said closure is 110 closed, said passageway being in alignment with the center of the deck opening.

3. An air lock comprising a cylindrical casing having a tapered lower end and a closed top provided with an opening, an eccentrically located circular door carried by the top of said casing, the edge of the door passing through the center of the top, a deck having a concentrically located door located near the bottom of said casing, gaskets secured to each of said doors for rendering the same air tight, means whereby both of said doors are operated from the top of said casing by one man, a passageway formed centrally of the top and equally divided between the top and the door carried thereby, and hardened wear plates surrounding said passage for preventing its enlargement due to the passage of a hoisting cable therethrough. 125 130

4. An air lock comprising a cylindrical member provided with a top having an eccentrically located circular opening therein, the edge of said opening passing through the center point of the top, a one piece hinged closure for said opening secured to the underside of the top, a second member secured to the lower end of the cylindrical member, a deck provided with a circular opening concentric with the cylindrical member secured within said second member, an air-tight one piece closure for said deck opening hingedly secured to the underside of the deck, means operable from the top of the cylindrical

member for operating said last mentioned closure, a guide-loop carried by said top for holding the last mentioned closure operating means in position, a passageway for a hoisting cable formed in the edges of the opening of the top and its closure, said passageway being in vertical alignment with the center of the deck opening, and hardened wear plates carried by the top and its door, each plate partially surrounding the passageway.

In testimony whereof we have affixed our signatures.

JOHN H. MURPHY.
ELSTON A. LOTZ.
